INVENTOR:

Edward Shaughnessy
BY David E. Carlson
ATTORNEY.

UNITED STATES PATENT OFFICE.

EDWARD SHAUGHNESSY, OF WEST ST. PAUL, MINNESOTA, ASSIGNOR OF ONE-HALF
TO MAX A. GROLLA, OF WEST ST. PAUL, MINNESOTA.

DISPLAY AND ILLUMINATING DEVICE.

Application filed December 4, 1926. Serial No. 152,671.

My invention relates to an illuminated license and signal device for automobiles and other vehicles and the object is to provide a simple efficient and inexpensive device particularly adaptable for motor vehicles. The device is used in pairs and involves the use of colored glass serving to display illuminated license plates in predetermined colors and incidentally serving as parking lights when the vehicle is not in motion.

In the accompanying drawing:

Fig. 1 is a top view of one unit of my device.

Fig. 2 is a partly sectional face view of Fig. 1.

Fig. 3 is an approximately full size cross section of a preferred type of lamp socket about as on line 3—3 in Fig. 1.

Fig. 4 is a wiring diagram of my device as used on an automobile.

Fig. 5 is a detail face view of a modified form of lamp socket.

Fig. 6 is a wiring diagram of a two-way switch system for controlling current to both lamps from a switch socket such as shown in Fig. 5 and located one at each illuminating device.

Referring to the drawing by reference numerals 10 designates a sheet metal reflector housing the front of which is of elongated quadrangular shape and open and said opening having inwardly directed flanges 10F on two long sides and one end while the other end is not flanged so as to slidably receive a colored glass 11 in front of which is a sheet metal license plate 12. The latter plate has suitable cut out numbers and lettering indicating the license number, State, year and class of car. The plates 11 and 12 are stopped by the end flange 10F and retained within the flanges, the position of said plates being shown dotted in Fig. 2 and there being a space between the free end of said plates and the adjacent end of the housing as at S in Fig. 2. 13 is a small screw or like means close to the open end of one or both parallel flanges 10F and located to prevent the plates 11—12 from slipping out of the device.

14 is an electric bulb removably fixed in the holder 15 of insulating material and suitably retained in a sheet metal sleeve 16 formed integral with the converging rearwardly slanting walls of the housing 10 (see Fig. 3) and forming the reflector means back of the license and colored plates.

17 is a threaded central bore in member 15 adapted to receive the threaded end of lamp 14. 18 and 18A are fixed contacts in holder 15 and of which 18 is connected to a center contact 19 in the bore 17 frictionally engaged by the threaded socket end of the lamp 14, and contact 18A has an exposed conductor 20 within bore 17 to be engaged by the threaded lamp socket to complete electric circuit through the lamp. Current is circulated through the lamp by a live contact 21 through a wire 22 and a contact 23 with wire 24, both said contacts 21 and 24 fixed in the end of bore 25 of an oscillatable cap 26, said bore normally occupied by the rear end of the plug 15 in which the contacts 18 and 18A are positioned to be simultaneously engaged by contacts 21 and 23. A slight turn of cap 26 separates the said contacts and opens the circuit to the lamp.

In Fig. 4, 27 is a battery or other source of current from which wire 22 extends to the switch described in the housing 10, current continuing from thence through wire 24 to the front housing or rear housing as the case may be and being grounded as at 28.

In the modified form in Figs. 5 and 6 there are three contacts 21, 23 and 23A in the cap 26 arranged close together. In this case the contacts 18 and 18A are also close together to contact simultaneously with any two of the three contacts 21, 23 and 23A. With this form of switch and wiring as shown in Fig. 6 there is a switch cap 26 at each housing and circuit is readily closed or opened to both illuminating devices by manipulating either switch. Thus the operator can switch on both lights from either end of the car.

I prefer to use red glass in the rear housing and green glass in the front housing to provide correspondingly illuminated license numbers and letters. These colors are the most commonly used for forwardly and rearwardly exposed parking lights but it is obvious that my device should remain lighted during dark hours and serve the double purpose of illuminating the license and parking lights. In localities requiring certain colors of lights for parking the law may be readily complied with by putting in glass of the required colors.

The circuit control means of my device are purposely placed at or within each housing or both housings. The driver of a car must leave his seat to turn the lights on and off and he will then know definitely when doing

so that his lights are on or off as needed and that when one is turned on the other is also on. Thus he need not bother with turning on parking lights even when the car is 5 stopped. Illuminated license plates will also comply with regulations requiring clearly exposed numbers and also provide readily readable identifying means. The latter feature makes it difficult for a driver to get away 10 from the scene of an accident without his number being easily obtained.

It is also obvious that in the use of my device so-called tail lights are not needed on a car.

15 I claim:

In an illuminating device for motor vehicles, having a source of electric current, and signal housings mounted one at each end of the vehicle, an electric lamp in each housing 20 in circuit with said source of electric current and means for regulating said circuit and fixed at each housing; each said housing comprising a quadrangular open frame, reflector panels formed integral with said frame ex-

tending from all four edges thereof angularly 25 toward a point of convergence centrally of and in spaced relation rearward of said frame, an electric bulb socket fixed at said latter point, a plate of translucent colored material adapted to be removably retained in said quadrangular frame, a sheet metal plate also removably retained in said frame and outwardly of said colored plate, said sheet metal plate having cut out parts in the form of suitably arranged letters and numbers, said 35 quadrangular plate retaining frame of each housing comprising on three adjoining sides a continuous inwardly opening channel, the fourth side being open to slidably insert said plates between the parallel channels into the 40 end channel, and means for retaining said plates in position, consisting in providing apertures in the channel members adjacent said open end, and a retaining element insertible in each said aperture in a position to prevent endwise movement of the plates.

In testimony whereof I affix my signature.

EDWARD SHAUGHNESSY.
